Attorney

UNITED STATES PATENT OFFICE.

HARRY C. ZIMMERMAN, OF WASHINGTON, DISTRICT OF COLUMBIA.

COUPLING.

Application filed September 11, 1924. Serial No. 737,177.

(GRANTED UNDER THE ACT OF MARCH 3, 1883; 22 STAT. L. 625.)

To all whom it may concern:

Be it known that I, HARRY C. ZIMMERMAN, a citizen of the United States, and a resident of Washington, District of Columbia, have invented an Improvement in Couplings, of which the following is a specification.

The invention described herein may be used by the Government, or any of its officers or employees in prosecution of work for the Government, or by any other person in the United States, without payment to me of any royalty thereon, in accordance with the act of March 3, 1883.

15 This invention relates primarily to means for connecting a gun to the reciprocating element of a recoil mechanism.

In artillery of small caliber of the type especially adapted to accompany infantry 20 troops on the advance or for use in mountainous regions, the guns are portable structures capable of rapid dismantling and assembly and divisible into convenient individual loads.

25 The object of the present invention is to provide a simple and efficient device for detachably and rapidly connecting a gun barrel to the reciprocating element of the recoil mechanism, the gun when lowered to its 30 sleigh or to the cradle being in position to be locked in place without the necessity of aligning or manipulating the connecting elements.

The invention consists in mounting a retaining ring on the reciprocating element and 35 forming a slot in said ring to receive the lug on the gun, the lug being lowered over and securely held by a locking bolt carried by the ring and extending across its slot.

40 To these and other ends, my invention consists in the construction, arrangement, and combination of elements, described herein-after and pointed out in the claim forming a part of this specification.

45 A practical embodiment of my invention is illustrated in the accompanying drawings, in which—

Fig. 1 is a view in side elevation of a gun in battery, the cradle broken away at its 50 rear end to show the gun and recoil mechanism connection;

Fig. 2 is a longitudinal sectional view of the rear end of the gun in battery;

Fig. 3 is an end view thereof;

Fig. 4 is a detailed side elevation of the 55 retaining ring;

Fig. 5 is an end view of the same;

Fig. 6 is a detailed view of the locking bolt; and

Fig. 7 is a sectional view taken on the line 60 7-7 of Fig. 6.

Referring to the drawings by numerals of reference:

According to the invention, the cradle 11 is provided with a top plate 12, having suitable guide-ways for reciprocally mounting 65 a sleigh 13 which carries the gun 14.

Within the cradle is a recoil cylinder 15 adapted to be guided in reciprocation by a stationary piston rod 16 secured to the front 70 cradle cover 17 and by an annular plate 18 which forms a bearing against which a spring 19 is compressed by a recoil cylinder head ring, not shown. The piston rod is provided at its rear end with a throttling 75 valve 20 and a regulator 21 and is further adapted to receive a buffer rod 22 carried by the cylinder.

The rear end of the cylinder is reduced 80 and threaded for the reception of a retaining ring 23, forwardly flanged as at 24, the flange retaining a drain plug 25. The upper portion of the ring is formed with a transverse slot 26 for the reception of a lug 27 on the gun 14, the lug having a central 85 longitudinal key hole slot 28 adapted to receive a bolt 29 mounted in a passage intersecting the transverse slot 26 and held against removal by a washer 30.

The portion of the bolt 29 which is disposed in the slot 26 is oblong in shape as indicated at 31 so that when the bolt is in unlocked position its narrow portion 31 will be parallel to and receivable through the restricted opening of the key hole slot 28 90 whence it may be turned in the circular portion of the key hole slot to dispose its widest surface at right angles to the restricted opening thereof (as shown in Fig. 2) to positively prevent disengagement of the lug 27. 100

The handle portion of the bolt 29 is provided with a plunger 32 engageable in recesses 33 to hold the bolt in its locked or released position.

An open annular reinforcing plate 34 at 105 the rear end of the cradle is designed to afford sufficient clearance for the retaining ring 23 when the gun moves in recoil.

The normal position of the retaining ring 23 prior to assembly of the gun is flush against the annular plate 18 so that when the gun barrel is mounted on its sleigh the 5 lug will be lowered directly into the slot on the ring, whereupon a quarter turn of the bolt completes the locking engagement.

As the gun when in use is generally assembled or dismantled under conditions of 10 darkness it is apparent that manipulation of the gun to align its connecting elements would be a difficult procedure.

While in the foregoing there has been illustrated and described such combination 15 and arrangement of elements as constitute the preferred embodiment of my invention,

it is nevertheless desired to emphasize the fact that interpretation of the invention should only be conclusive when made in the light of the subjoined claim.

I claim:

The combination with a reciprocating member of a retaining ring on one end thereof, said ring formed with a transverse slot and an intersecting passage, a bolt in said passage having a narrow portion disposed in the transverse slot, means for holding the bolt in locked or unlocked position, and a lug having a key hole slot centrally in its underface for receiving the narrow portion of the bolt.

HARRY C. ZIMMERMAN.
